UNITED STATES PATENT OFFICE.

JOHANN JURGEN RICHARD HAALCK, OF SALTAIR, UTAH.

TRANSPORTING APPARATUS.

1,283,744.

Specification of Letters Patent. Patented Nov. 5, 1918.

Application filed July 24, 1918. Serial No. 246,619.

To all whom it may concern:

Be it known that I, JOHANN JURGEN RICHARD HAALCK, a subject of the Emperor of Germany, residing at Saltair, in the county of Salt Lake and State of Utah, have invented certain new and useful Improvements in Transporting Apparatus, of which the following is a specification, reference being had to the accompanying drawings.

10 This invention relates to transporting apparatus, and more particularly to certain improvements in an apparatus of the character shown and described in Patent No. 1,259,619, issued to me March 19, 1918.

15 It is the primary object of the present invention to provide an apparatus of the character referred to for transporting freight boats and other vessels over unnavigable portions of rivers or for removing the vessel from the river and placing it in a canal for the continuation of its travel.

It is a more particular object of the invention to provide a traveling support having means for hoisting or raising a vessel, 25 track rails upon which said support is mounted to travel, and means geared to the track rails and controllable by an operator on the support, whereby the support and the vessel carried thereby may be moved in 30 either direction.

It is also one of the important objects of the invention to provide an improved mounting and arrangement of the vessel hoisting and suspending means upon the support so 35 that the vessel will at all times remain in a horizontal plane irrespective of the grade upon which the support may travel.

And it is a further general object of my invention to improve the original apparatus in the particulars above referred to without greatly complicating the construction thereof or increasing its manufacturing cost.

With the above and other objects in view, the invention consists in the improved construction, combination and relative arrangement of the several parts as will be herein-after more fully described, subsequently claimed and illustrated in the accompanying drawings in which similar reference characters designate corresponding parts throughout the several views, and wherein:

Figure 1 is a side elevation of the apparatus, showing the same arranged for the transportation of vessels over a dam;

Fig. 2 is a similar view, showing the ar-

rangement of the trackage upon which the apparatus moves, for transporting a vessel from a river to a side hill canal:

Fig. 3 is an end elevation;

Fig. 4 is a plan view, the swinging support for the traveling means being removed;

Fig. 5 is an enlarged detail section taken on the line 5—5 of Fig. 4;

Fig. 6 is a plan view illustrating the manually operable control means for the driving trucks; and

Fig. 7 is a plan view showing the means arranged at the opposite ends of the track rails to guide or direct the vessel to the apparatus.

Referring in detail to the drawings, 5 designates a suitable trussed or braced skeletonized structure having a base portion, generally indicated by the numeral 6, and 75 upright side portions, designated 7. At the opposite ends of the structure 5, and at each side thereof, the supporting trucks 8 are arranged, each truck carrying an axle 9 mounted to rock in a bearing 10 secured to 80 the base 6 of the frame structure. Each of the trucks 8 is equipped with two pairs of truck wheels 11, each wheel having a series of cog teeth 12 on each side of a central annular flange 13.

The apparatus is mounted to travel upon track rails 14 which are arranged in spaced pairs. The rails in each pair are suitably spaced to receive the flanges 13 of the wheels 11 between them, and each rail is toothed, as 90 shown at 15, for engagement of the cog teeth 12 therewith. Thus, the truck wheels are effectually held against transverse, shifting movement and the possible derailing of the apparatus is obviated. The rails 14 are supported upon suitable ties 16, to which they are fixed, and these ties may be anchored in any suitable manner.

Upon the upper ends of the side portions 7 of the frame 5, the bearing blocks 17 are 100 fixed to receive the ends of a rock shaft 18, from which a second frame structure 19 is suspended. This frame 19 may be of similar construction to that disclosed in my issued patent hereinbefore referred to and carries 105 the traveling cranes and the mechanism whereby the vessel may be elevated or hoisted above the water. As these cranes and the hoisting mechanism are fully shown and described in my prior patent, they will 110 not be herein further referred to in detail. It will suffice to state that the power for the

operation of the cranes and the hoisting mechanism is obtained from a trolley 20 which is operatively engaged with a current supply wire 21.

5 The frame 19 is, of course, provided with an operator's compartment, from which point the direction of travel of the apparatus is controlled. Preferably, each pair of truck wheels 11 is positively driven, and to this 10 end a sprocket wheel 22 is centrally fixed upon the axle 23 of each pair of wheels. The spaced sprockets 23 are connected by means of an endless chain 24 to a similar sprocket wheel 25 which is loosely mounted upon the 15 axle 9. To one side of this latter sprocket wheel, a beveled gear 26 is suitably fixed or may be integrally formed therewith. At each side of the base 6 of the frame structure 5, a pair of shafts 27 are rotatably 20 mounted in suitable bearings and extend longitudinally in opposite directions from the center of the frame. A beveled gear 28 fixed upon one end of each of said shafts meshes with the gear 26 on the sprocket 25 25 at one end of the frame. A similar gear 29 is also fixed upon the other or inner end of each shaft 27. These gears 29 mesh with the beveled gears 30 on the opposite ends of a transverse shaft 31 suitably mounted upon 30 the base 6 of the frame. An additional beveled gear 32 is fixed upon the shaft 31 intermediate of its ends and with this latter gear, the beveled gear 33 on the lower end of a vertically disposed shaft 34 is engaged. 35

Upon a suitable support, indicated at 35, mounted in one side center of the frame structure, a shaft 36 is arranged and driven by means of a motor, indicated at 37. Upon 40 the shaft 36 a sprocket wheel 38 is loosely mounted and in spaced relation to said sprocket wheel, a gear 39 is also loosely mounted on said shaft. A second shaft 40 is arranged in parallel relation to the shaft 45 36, and has a beveled gear 41 fixed to one of its ends meshing with a similar gear 42 on the upper end of the vertical shaft 34. A sprocket wheel 43 fixed on the shaft 40 is connected by the endless chain 44 to the 50 loose sprocket 38. A relatively large gear wheel 45 is also fixed upon the shaft 40 and meshes with the loose gear 39 on the shaft 36. A manually operable, shiftable clutch 46 and 47 respectively is provided for the 55 sprocket 38 and gear 39, whereby they may be independently locked to the shaft 36 for rotation therewith. It will be apparent from this construction that when the sprocket 38 is clutched to the shaft 36, the 60 truck wheels 11 will be positively driven through the gearing described in one direction, and by co-operation with the gear or toothed rails 14, the entire structure will be moved longitudinally. Upon releasing the 65 sprocket 38 and locking the gear 39 to the

shaft 36, the apparatus will be moved in the opposite direction, owing to the fact that said gear has direct meshing engagement with the gear 45 on the power transmission shaft 40.

At each end of the track rails 14, and in spaced relation thereto, a guideway for the vessel is provided, said way being formed by the walls 48 which are suitably supported and braced and converge longitudinally toward the track. To the side portions 7 of the frame structure 5, vertically spaced, longitudinally extending bars 49 are secured, and in each of these bars a series of spaced, upstanding pins 50 are fixed. 80 These pins provide convenient means whereby a cable or other article may be employed for properly directing the vessel in its movement between the walls 48 into the frame structure 5. 85

In Fig. 1 of the drawings, I have shown the apparatus arranged for the purpose of transporting vessels over a dam. As the vessel approaches the dam, it is guided between the side portions 7 of the frame structure in the manner just stated, and the cranes on the superposed frame 19 are operatively positioned so that the hoisting cables may be connected to the vessel. The vessel is then raised or elevated above the surface 95 of the water. The operator then starts the motor 37 in operation to guide the truck wheels in the proper direction and causes the entire apparatus to travel longitudinally on the rails 14 and over the dam to the opposite side thereof. In ascending or descending a grade, the frame 19 and the vessel carried thereby may swing freely with respect to the frame structure 5 so that the vessel will at all times remain in a horizontal position. After reaching the opposite side of the dam, the vessel is again lowered to the water and the cables disconnected. 100

In Fig. 2 of the drawings, I have shown the arrangement of the apparatus, when the vessel is to be transported to a side hill canal which parallels an unnavigable stretch of the river. The track rails are, of course, properly laid so as to convey the vessel upwardly and in a lateral direction from the 110 river to the canal. 115

From the foregoing description, taken in connection with the accompanying drawings, the construction, manner of operation and several advantages of my improved transporting apparatus will be clearly and fully understood. The several improvements which I have made in the original apparatus are of a relatively simple character so that the construction thereof is not greatly complicated. The apparatus can therefore be installed and maintained in operation at relatively small cost. It is apparent, of course, that the specific construction of the frames 5 and 19 might be greatly varied 120 125 130

from that indicated in the accompanying drawings. The several other parts of the apparatus are likewise susceptible of many modifications, and it is, therefore, to be understood that I reserve the privilege of adopting all such legitimate changes as may be fairly embodied within the spirit and scope of the invention as claimed.

1. claim:—

- 10 1. In a transporting device, a traveling supporting structure, a superstructure mounted to swing upon the supporting structure, hoisting means arranged upon the superstructure, and propelling mechanism for the supporting structure.
- 15 2. In a transporting device, a traveling supporting structure, a superstructure mounted to swing upon the supporting structure, hoisting means arranged upon the superstructure, and manually controllable means operable from the superstructure for moving the supporting structure in the desired direction.
- 20 3. In a transporting device, track rails, a supporting structure geared to the track rails to travel thereon, a superstructure mounted for swinging movement upon said supporting structure, hoisting means arranged upon the superstructure, and propelling mechanism for the supporting structure controllable from the superstructure.
- 25 4. In a transporting apparatus, track rails, a supporting structure, trucks for said supporting structure having driving wheels geared to the track rails, a superstructure mounted for vertical swinging movement upon the supporting structure, and mechanism for positively operating all of the truck wheels to move the supporting structure in the desired direction.
- 30 5. In a transporting apparatus, a sup-

porting structure, a plurality of trucks upon which said structure is mounted, each truck having a series of supporting wheels, a superstructure mounted upon the supporting structure, and gearing for positively operating all of the truck wheels, said gearing being controllable from the superstructure to move the supporting structure in the desired direction.

45 6. In a transporting apparatus, a supporting structure, a plurality of trucks upon which said structure is mounted, each having a plurality of supporting wheels, gearing mounted upon the supporting structure to positively drive all of the supporting wheels, a superstructure mounted for swinging movement upon the base structure, hoisting means carried by the superstructure, and means manually controllable from the superstructure to actuate the gearing and move the supporting structure in the desired direction.

50 7. In a transporting apparatus, track rails, a supporting structure, a plurality of trucks upon which said structure is mounted, each truck having a series of wheels geared to the track rails, gearing for positively operating all of the truck wheels, a superstructure mounted upon the supporting structure, hoisting means carried by the superstructure, and means manually controllable from the superstructure to actuate said gearing and move the supporting structure in the desired direction.

55 75 In testimony whereof I hereunto affix my signature in the presence of two witnesses.

JOHANN JURGEN RICHARD HAALCK.
